UNITED STATES PATENT OFFICE.

CARLTON L. KENNEDY, OF BRAINTREE, MASSACHUSETTS, ASSIGNOR TO THE HOLTZER-CABOT ELECTRIC COMPANY, OF ROXBURY, MASSACHUSETTS, A CORPORATION OF MASSACHUSETTS.

SHORT-CIRCUITING DEVICE FOR ELECTRIC MOTORS.

Application filed May 25, 1927. Serial No. 194,026.

The present invention relates to improvements in short-circuiting devices for electric motors, and more particularly to induction motors.

5 The invention constitutes an improvement on the construction of the Kennedy Patent No. 1,145,594, dated July 6, 1915.

In the accompanying drawings illustrating the preferred form of the invention, 10 Fig. 1 is an end elevation of a commutator with the improved short-circuiting devices applied thereto; Fig. 2 is an axial section of the commutator showing the short-circuiting devices in operative position; Fig. 3 15 is a similar section with the short-circuiting devices inoperative; Fig. 4 is a perspective view of a contact; and Fig. 5 is a perspective view of the lever devices.

The illustrated embodiment of the invention is described as follows: The commutator segments 10 are mounted upon a commutator spool 11 which is rigidly secured to the rotor shaft 12. The inner end of the spool has an outwardly projecting flange or 20 lip 13, having a beveled inner face. The inner end of the periphery of the spool carries a ring or follower 14, which has a beveled inner face similar to that of the flange 13, and it is secured in place by spinning a thin lip 15 of the spool over the outside surface of the ring 14. The commutator segments are firmly positioned between the lip or flange 13 of the ring 14, being insulated from them in the usual manner.

25 Between the commutator spool and the rotor shaft is formed a contact carrier or rocker arm chamber 16. Within this chamber are received the rocker arm devices shown in Fig. 5 and indicated in a general 30 way by the reference character 17. In the construction shown in the drawings eight of these rocker arm devices are employed. Each device has a base 18, having a curved edge at 19 to fit the rotor shaft, and two 35 arms 20 and 21 which extend at right angles from the base 18 outwardly, as shown in Figs. 2 and 3. The ends of these arms carry hooks 22 upon which the contact blocks 23, shown in Fig. 4, are supported.

40 The rocker arm devices are arranged in the rocker arm chamber with their bases radially arranged around the shaft. The inner ends of the bases are engaged by the washer 24, which embraces the shaft and is

forced toward the bottom of the rocker chamber by the spring 25, the outer abutment of which is formed by the nut 26 first turned to the correctly adjusted position, and then secured in such position by prick-punching the thread so the nut cannot work 55 loose.

The pressure of the rocker spring 25 normally tends to hold the rockers in the position shown in Fig. 3. Upon the hooks of the rocker arms are supported the contact 60 blocks 23. There are sixteen of these blocks, one for each hook of the rocker arm devices. These contact blocks are made of sheet copper stamped and formed in the shape illustrated. The contact blocks consist of two 65 radiating contact members 27, extending from the base 28, provided with a hole 29 which slips over the hook 22. Each contact member is provided with a protuberant contact portion 30. As seen in Fig. 2, the contact block is so supported on the carrier that the point 31 of the hook engages the inner margin of the base 28 of the block, as a consequence of which, when the shaft rotates at any speed beyond the critical speed, the contact block assumes the position shown in Fig. 2, and the contact portions of the radiating 70 members of the block engage the commutator segments 10, thereby short-circuiting the commutator at a large number of 75 points, as shown.

This construction of short-circuiting device has all of the good features of operation which the construction of the Kennedy patent referred to has, and in addition it is 80 much lighter, cheaper, simpler and more durable. Thus, the rocker arm devices are made of stamped sheet metal, whereas the rocker arms of the patent are made of castings and required to be machined. Again, 85 the contact blocks of the present construction are similarly made of stamped sheet metal, which is much less expensive than the cast contact blocks of the patent. Furthermore, the use of a pivot pin in the 90 patent construction requires the drilling of holes and the fitting and riveting of the pins or pintles in place, whereas in the present construction the contact blocks are merely hooked on the hooks of the rocker arm devices before the devices are moved into the 95 rocker arm chamber. The pivot of the contact blocks of the patent occupies a posi- 100 105

tion very much the same as that of the position of the point of the hook of the rocker arms of the present construction, and the operation of the devices is the same in that when the motor is at rest, the rocker arm devices and contact blocks occupy the position shown in Fig. 3. After the rotation begins centrifugal force causes the contact blocks immediately to assume the position shown in the lower part of Fig. 3, and then when the critical speed is reached, the rocker arm devices move outwardly to the position shown in Fig. 2, and the blocks then occupy the position shown in Fig. 2, short-circuiting the commutator. The outward throw of the rocker arm devices is limited by their engagement with the inner wall of the rocker arm chamber, and when the parts have assumed the position just described the motor operates as an induction motor.

As in the construction of said patent, by properly adjusting the strength and tension of the spring 25 to the weight of the contact blocks and the weight of the rocker arms, the centrifugal force due to the outward travel of the blocks may be made to increase faster than the increase in the tension of the spring, with the result that the blocks will attain a short-circuiting position on the commutator by a quick movement.

Having thus described the invention, what is claimed is:

1. A short-circuiting device for electric motors having, in combination, a plurality of tippingly mounted rocker arm levers each provided with a hook, and a contact

block loosely hung on the hook adapted to engage the commutator.

2. A short-circuiting device for electric motors having, in combination, a plurality of pairs of tippingly mounted rocker arm levers each provided with a base and with a hook, and a contact block having a hole to receive the hook on which the block is loosely hung.

3. A short-circuiting device for electric motors having, in combination, a plurality of tippingly mounted rocker arm devices comprising a base, two arms arranged at right angles to the base, the arms provided on their ends with hooks, and a contact block comprising a base provided with a hook hole and two radiating contact members extending outwardly from the base.

4. A short-circuiting device for electric motors having, in combination, a plurality of tippingly mounted rocker arm devices each provided with a base having arms extended substantially at right angles thereto located between the ends of the base, a rotor shaft, a spring encircling the shaft adapted to engage one end of the bases of the rocker arm devices, normally acting to hold the latter in position with their arms extending parallel with the shaft, the rocker arms being provided on their outer ends with outwardly extended portions having hooks on their ends and contact blocks hung upon the hooks.

In testimony whereof I have signed my name to this specification.

CARLTON L. KENNEDY.
